No. 15,027

May 27, 1884

UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,027, dated May 27, 1884.

Application filed March 27, 1884. Term of patent 3½ years.

To all whom it may concern:

Be it known that I, SARAH JANE SHIELS, of the city, county, and State of New York, have invented and produced a new and original Design for a Pattern of a Miss's Costume, (numbered 9,145;) and I do hereby declare that the engraved prints accompanying this specification convey to any one accustomed to using paper patterns a clear understanding of how a garment made up by the pattern will appear.

The design shows a walking-skirt and an overdress. The skirt displays a side plaited panel on the left side of the front. The over-dress exhibits close-fitted basque-fronts, with 15 a diagonal closing and depending plain draper-

ies flaring at the lower end of the closing, a deep polonaise - back displaying under-folded plaits at the lower ends of its middle three seams; coat-sleeves, a cape-collar, and a standing collar.

What I claim as my invention, and desire to secure by Letters Patent, is—

The design for a miss's costume, as shown in the engraved prints accompanying this specification.

SARAH JANE SHIELS.

Witnesses:

ALFRED FRANCIS,
JOHN HENRY DRURY.
